UNITED STATES PATENT OFFICE

LAWRENCE S. LAMB, OF DETROIT, MICHIGAN, ASSIGNOR TO HUDSON MOTOR CAR COMPANY, OF DETROIT, MICHIGAN, A CORPORATION OF MICHIGAN

APPARATUS FOR FORMING OFFSET FLANGES ON SHEET METAL PANELS AND THE LIKE

Application filed December 12, 1927. Serial No. 239,282.

This invention relates to the manufacture of sheet metal for metal automobile bodies and particularly to the formation on such a panel of an offset flange for carrying a weather strip adapted to engage the glass for the window opening.

In a co-pending application Serial No. 240,891 filed December 17, 1927, by Russell E. Hansen and Otto J. Groehn, (Patent No. 1,749,184, dated March 4, 1930) apparatus has been described for expanding and setting the window opening of a door panel of the type to which the present invention relates and also for turning under the flange of the window opening. It is an object of the present invention to provide a method and apparatus for offsetting a flange but in its more specific aspect is directed to offsetting an undeturned flange of the type above mentioned to a position suitable for carrying a weather strip. In the practice of the invention an apparatus is employed comprising upper and lower dies which are arranged for relative movement and are positioned normally to provide a hollow shaped mold space or die over which the flange to be offset is placed. Relative movement of the upper and lower die members causes a pressure to be exerted upon the flange to bend it inwardly along the previously weakened line of bend and in the opposite direction along a line spaced therefrom. The upper and lower dies are arranged so that the principal bending pressure is applied to the flange along a path intersecting the second line of bend.

Before explaining the invention in detail it is pointed out that the embodiment of the invention herein described is merely for the purpose of illustration and that the invention is not thereby limited except as defined by the appended claims.

The invention will be more clearly understood from the following description in conjunction with the accompanying drawings, in which:

Fig. 1 is a plan view of an apparatus embodying the invention;

Fig. 2 is an elevational view of the same;

Fig. 3 is a sectional view taken upon the line 3—3 of Fig. 2 and showing the relation

of the parts at the beginning of operations;

Fig. 4 is a sectional view similar to that of Fig. 3 showing the relation of the parts at the completion of operations;

Fig. 5 is a fragmentary perspective view 55 of an outside panel for an automobile door having the window opening flange offset in accordance with the provisions of the invention; and,

Fig. 6 is a fragmentary vertical section of 60 an automobile door showing the weather strip mounted on the offset flange of the outside door panel.

In the drawings an automobile door is illustrated (Fig. 6) having an outside panel 65 10 which is shaped as described in the above mentioned co-pending application to provide a window opening 11 having an undeturned flange 12. In the embodiment of the invention illustrated the undeturned 70 flange 12 is offset so that a weather strip 13 may be secured thereto in any suitable manner as by a nut 14 and bolt 15 to engage the glass 16 between the inside panel 17 and the outside panel 10.

In the practice of the invention advantage is taken of the weakened condition of the metal along the line of bend where the flange of the window opening has been turned under previously as described in the above mentioned co-pending application. Thus, the undeturned flange 12 is bent inwardly along the previously weakened line of bend 18 and then bent outwardly or in the opposite direction along a line spaced from said weakened line of bend.

A suitable apparatus for accomplishing this comprises a base 20 having spaced upwardly stepped projections 21 and 22. A gauge or guide 23 is secured at its lower end 90 to the base 20 in any suitable manner as by bolts 24 and is provided at its upper free end with an inwardly curved portion 25. A stationary lower die member 30 is positioned upon the top surface or projection 21 and is 95 suitably secured to the side surface 31 of projection 22 in any suitable manner as by screws 32. A suitable guide 33 is positioned upon the top surface of the base 20 and against the side surface 34 of projection 21 100.

and is suitably secured to the base as by screws 35. A yieldingly movable lower die member 38 is positioned and guided between the stationary die member 30 and the guide 5 33 and is provided with a lateral projection 40 at its lower end which is held normally in a raised position against a shoulder 41 upon the stationary die member 30 by springs 42 extending between openings 43 in the base 20 10 and openings 44 in the die member 38. The die member 38 is provided at its upper end with a portion 46 overhanging and normally spaced from the stationary die member 30. An upper die 50 is positioned appropriately 15 upon a vertically reciprocable ram 51 and is suitably secured thereto as by screws 52. The adjacent surfaces of the die members 30, 38 and 50 are arranged substantially parallel.

In operation the panel 10 is positioned to 20 rest upon the yieldingly movable lower die member 38, and preferably at an angle to the movement thereof, with the portion 46 thereof within the undeturned flange 12 and with an upper portion of the door panel 25 engaging the lower surface of the curved portion 25 of the guide 23. With the panel thus positioned, the upper die 50 is caused to move downward to engage a portion of the panel resting upon the yieldable member 38 and 30 cause the latter to move downward yieldingly and thereby bring the undeturned flange 12 into engagement with the top surface of the stationary lower die member 30. Further downward movement of the upper die 35 50 and the yielding lower die member 38 causes the stationary die member 30 to exert a pressure upon the undeturned flange 12 to bend the latter inwardly along the previously weakened line of bend 18 and bend or 40 crease it in the opposite direction along a line spaced from said weakened line of bend by jamming between the adjacent surfaces of the upper die 50 and yielding lower die 38 and stationary lower die member 30. When 45 the upper die is raised, the springs 42 move the die member 38 together with the door panel 10 upward thereby permitting the removal of the panel from the machine.

I claim:—

50 1. An apparatus for offsetting a portion of the flange of the window opening of a metal automobile body door panel turned under along a given line to form a weather strip flange comprising a lower die having a 55 yieldingly movable die member arranged to support the door at an angle to the movement thereof and fit within the space between the same and the undeturned flange with the latter spaced from said member, said lower 60 die including also a stationary die member adapted to engage the undeturned flange, and an upper die movable in the direction of movement of said yielding member toward said lower die members to grip the 65 panel on said yieldable member and cause the

undeturned flange to bend along the line of previous bend and thereafter wedge the same between the lower die members and the upper die.

2. An apparatus for offsetting a flange 70 comprising a lower stationary die member, a yieldingly movable lower die member having a portion overlapping and normally spaced from said stationary member, an upper die overlapping the movable and stationary lower die members and movable towards the same, the stationary lower die member having intersecting top surfaces one of which is parallel to the adjacent surface of the overlapping portion of the movable lower die member and the other surface being parallel to the adjacent surface of the upper die whereby upon downward movement of the upper die said flange is offset an amount depending upon the line of engagement of said 80 flange with the intersection of said top surfaces.

3. An apparatus for offsetting a flange comprising a lower die, and an upper die movable toward and away from the lower die, said 90 lower die having a stationary member and a member yieldingly movable in the direction of movement of the upper die with a portion overlapping said stationary member, said upper die having one portion adapted to engage both the movable and stationary member of said lower die.

4. An apparatus for offsetting a flange comprising a lower die, and an upper die movable toward and away from the lower die, 100 said lower die having a stationary member and a member yieldingly movable in the direction of movement of the upper die with a portion overlapping said stationary member, said stationary member having inclined intersecting surfaces one of which is arranged to cooperate with a surface of said movable member and the other of which is arranged to cooperate with a surface of the upper die.

In testimony whereof I affix my signature. 110
